UNITED STATES PATENT OFFICE.

JOSEPH KAHN, OF DETROIT, MICHIGAN.

SAFETY-POCKET FOR GARMENTS.

SPECIFICATION forming part of Letters Patent No. 283,609, dated August 21, 1883.

Application filed December 23, 1882. (No model.)

To all whom it may concern:

Be it known that I, JOSEPH KAHN, of Detroit, in the county of Wayne and State of Michigan, have invented new and useful Improvements in Lock-Pockets for Garments; and I hereby declare that the following is a full, clear, and exact description thereof, reference being had to the accompanying drawings, which form a part of this specification.

10 This invention relates to certain new and useful improvements in the construction of safety-pockets for garments; and the invention consists in the peculiar construction of a pair of jaws designed to be inserted in the mouth of the pocket, all as more fully hereinafter set forth.

Figure 1 is a perspective view of my device detached. Fig. 2 is a sectional view, showing the device applied to a pocket. Fig. 3 is a detail view, showing the jaw bent, forming a recess to receive a watch-chain.

In the accompanying drawings, A A' represent the jaws of my device, which are pivotally secured together by a rod, a, passing through ears a', bent inwardly or at right angles with their respective jaws, as shown by Fig. 1, and the rods provided with a suitable spring, b, to throw the jaws open when released by the spring-lock B, and at these points I secure suitable springs, b, with which the hook c' upon the jaw A' engages. When the jaws are closed, the pin d, which disengages the hook, projects through a hole, e. In practice these jaws are secured in the mouth of the pocket and are entirely hid from view, as shown in Fig. 2, the head of the stud or pin d being underneath the cloth.

By the use of this device the pocket can be locked, and will prevent the accidental loss of articles from the pocket, while it will 40 also prevent the pickpocket from so successfully plying his vocation. These jaws will necessarily have to be made in different shapes, to correspond to the pocket in which they are to be used, and for watch and pistol pockets 45 the outer jaw should be bent, as shown by dotted lines at c in Fig. 1, so that the chain will not be clamped between the jaws when they are closed.

What I claim as my invention is—

1. In a safety-pocket for garments, the combination of two hinged jaws, the outer of which is bent out at c to receive the chain of a watch, as set forth.

2. The combination, in a safety-pocket for 55 garments, of the hinged jaws A A', the latter having an aperture, e, to receive the pin d, with the spring-lock B and hook c'.

3. In a safety-pocket for garments, the combination of the jaws A A', pivoted together by 60 a pin, a, passing through ears a', projecting at right angles with the side of the jaws, the ears of the jaw A' being arranged between those of the jaw A, adapting said jaw A' to fit snugly against the jaw A, in combination with the 65 spring b, spring-lock B, and hook c', all constructed and arranged substantially as shown and described.

In testimony that I claim the above as my invention I hereunto set my hand.

J. KAHN.
